UNITED STATES PATENT OFFICE

147,832

DESIGN FOR A PROJECTION MACHINE

Arthur J. Bradford, Wilmette, Ill., assignor to
Motion Picture Engineering Corporation, a cor-
poration of Illinois

Application September 19, 1946, Serial No. 133,417

Term of patent 14 years

(Cl. D61—1)

To all whom it may concern:

Be it known that I, Arthur J. Bradford, a citizen of the United States, residing at Wilmette, county of Cook and State of Illinois, have invented a new, original, and ornamental Design for a Projection Machine, of which the following is a specification, reference being had to the accompanying drawing, forming a part thereof, in which—

Fig. 1 is a top plan view of the projection machine showing my new design;

Fig. 2 is a front elevational view thereof;

Fig. 3 is a side elevational view thereof looking from the left in Fig. 2;

Fig. 4 is a side elevational view thereof looking from the right in Fig. 2; and

Fig. 5 is a rear elevational view thereof.

I claim:

The ornamental design for a projection machine, as shown.

ARTHUR J. BRADFORD.
